LIGHTING SYSTEM EMBODYING TWO OR
MORE ARC DISCHARGE DEVICES AND
BALLAST THEREFOR

Leopold Mauerer, Chicago, Ill., assignor to Jefferson Electric Company, Bellwood, Ill., a corporation of Illinois

Application April 15, 1946, Serial No. 662,136

5 Claims. (Cl. 315—254)

1

This invention relates to lighting systems embodying two or more arc discharge devices, such as fluorescent lamps, and in particular, to an improved electrical apparatus for supplying such discharge devices with electrically displaced operating currents, for the purpose of reducing stroboscopic effect and improving the power factor.

These supply devices, commonly called ballasts, have, in the past, been of two principal types. The first type consists of the combination of an auto transformer which supplies the necessary voltage for striking the arc, together with two reactors, one for each lamp, a condenser being connected in series with one of the reactors to provide the current displacement necessary to reduce stroboscopic effect and to correct the power factor. The second type consists of a high reactance transformer having a primary and two loosely coupled secondaries, a condenser being connected in series with one of the secondaries. The transformer may be either double wound, or an auto transformer, and in the latter instance, the total of the output voltage for each secondary circuit is made up of the sum of the primary voltage plus the secondary voltage.

This invention relates to the second type of ballast. Such ballasts have a serious shortcoming in that the leading secondary circuit delivers a distorted or peaked current wave to the lamp, which shortens the lamp life and also causes a more pronounced stroboscopic effect. Furthermore, ballasts of this type often deliver an insufficient amount of power to the leading lamp circuit.

The above mentioned distortion of the current wave is caused by magnetic saturation in the laminations of the leading secondary circuit. The high flux density which causes this saturation is not intentionally designed into the transformer, but is the result of the unusual phase relations existing in a high reactance transformer operating into a capacitative circuit. The result of this type of operation is a voltage across the leading secondary circuit which is considerably in excess of the normal open circuit voltage for which such transformers are usually designed and dimensioned. If, therefore, according to the present commercial practice, the transformer is designed so as to deliver the usual secondary circuit voltage necessary to strike an arc, and if, for reasons of economy, the core is designed so that the flux density approaches the saturation point under such open circuit conditions, then under operating conditions, when the secondary

2

circuit feeds into a load circuit which includes a lamp as well as a condenser, the voltage, and therefore the flux density in the leading secondary magnetic circuit, will increase to considerably higher values, which in turn, will cause distortion of the current wave shape, due to magnetic saturation.

It is an object of this invention to provide an improved lighting circuit in which the arc discharge devices have a longer life, and in which the stroboscopic effect is reduced and the power factor improved.

It is a further object of this invention to provide in a fluorescent lamp system of the type described, a ballast of the high reactance transformer type which will be free from the shortcomings outlined above.

I have found that these objects can be attained by providing a lighting system in which the flux density in the leading secondary magnetic circuit is substantially the same as the flux density of the lagging secondary magnetic circuit under operating conditions. Thus, not only do I achieve uniform intensity of illumination in both lamps, and improved lamp life, but I am also enabled to improve the current wave shape in the leading secondary circuit, and with respect to the system as a whole, to reduce stroboscopic effect and improve the power factor.

Still another object of this invention is to provide an improved ballast for a lighting system of this type in which the core for the leading secondary magnetic circuit is provided with a larger cross sectional area than the core for the lagging magnetic secondary circuit.

A still further object is to provide, in a system of this type, an improved core structure for the ballast which facilitates the assembly of the elements.

Other objects, features and improvements will become apparent as this description proceeds.

With reference now to the drawings, in which like reference numerals designate like parts—

Fig. 1 is a sectional elevation of a ballast embodying my invention;

Fig. 2 is a section taken along line 2—2 of Fig. 1;

Fig. 3 is a sectional view of a modified form of ballast;

Fig. 4 is a diagram of the lighting system as a whole; and

Figs. 5 and 6 are diagrams of a modified system.

In Fig. 4 the ballast is designated generally by the reference numeral 10, and it comprises a primary winding 11, a lead secondary winding 12, and a lag secondary winding 13, the windings be-

ing connected in autotransformer relationship. Arc discharge devices, such as fluorescent lamps 16 and 17, are provided for each of the secondary circuits, which may be referred to as the lead secondary circuit 24, and the lag secondary circuit 25. The lead secondary circuit 24 includes a condenser 14 which is connected in series with the lead secondary winding 12 and the lamp 16.

To the terminals 22 and 23 of the primary winding 11 are connected power leads 15. The lead secondary circuit 24 includes the primary winding 11, the secondary winding 12 which is connected to the terminal 23 of the primary winding by a conductor 20, the condenser 14, conductor 18 which connects the condenser to the lamp 16, the lamp 16 itself, and a portion of a T-connection 21 which connects the lamp 16 to the terminal 22 of the primary. The lag secondary circuit includes the primary winding 11, the secondary winding 13, a conductor 19 connecting the secondary winding to the lamp 17, the lamp itself, and a portion of the T-connection 21.

In operation it will be seen that the lead circuit 24 will be energized by a leading current, due to the preponderance of the capacitative reactance provided by the condenser 14 over the inductive reactance provided by the secondary 12. The lag circuit 25 will be energized by a lagging current, due to the inductive reactance of the secondary 13.

The core of the ballast 10, shown in Fig. 1, comprises a stack of E laminations 30 which are maintained in abutting relationship with an oppositely disposed stack of E laminations 31. It will be observed that the laminations 30 are of greater width than the laminations 31. The laminations may be maintained in their respective stacks, and in abutting relationship by suitable core clamping means, not shown.

The lead secondary 12 is disposed on the middle leg of the E laminations 30, and the lag secondary 13, together with the primary winding 11, are both disposed on the middle leg of the laminations 31. The lag secondary 13 and the primary winding 11 are spaced from each other, and magnetic shunts 32, together with fiber gaps 33, are interposed between these two windings. Thus a shunt path of comparatively low reluctance is provided between the primary and the lag secondary, which serves to increase the leakage reactance in the lag circuit.

The positions of the primary winding 11 and the lead secondary 12 on their respective cores are such that when the stacks of laminations are assembled, the primary is spaced from the lead secondary 12, as shown in Fig. 1. Thus flux leakage paths 34 are provided between these windings, the flux leakage paths, however, providing a path of somewhat greater reluctance than that provided by the magnetic shunts 32.

From an inspection of Fig. 1, it is obvious that the core of the lead secondary can carry a greater flux than the core of the lag secondary, the parts preferably being proportioned so that the flux density in each part of the core is substantially the same under normal operating conditions. The particular arrangement shown, consisting of two abutting stacks of E laminations, makes for simplicity in assembling the transformer, inasmuch as it requires the provision of only two different types of laminations.

In the embodiment of my invention which is herein shown and described, the secondary windings 12 and 13 are preferably proportioned so as to apply substantially equal voltages to the cir-

cuits 24 and 25 under open circuit conditions, that is, before an arc is struck across the lamps. However, after the arc has been struck, and the circuit established, the voltage in the lag circuit 25, including the winding 13, will be lower than the voltage under open circuit conditions, due to the leakage reactance, while the voltage in the lead circuit 24, including the winding 12, will be greater than the open circuit voltage. Therefore, since the flux is proportional to the voltage, the flux in the lamination stack 30 will be greater than the flux in the corresponding portion of the lamination stack 31. Due to the increased cross section of the lamination stack 30, the flux density may be maintained below the saturation point so that the current wave in the lead circuit 24 is not distorted.

The modified form of ballast 40 shown in Fig. 3, includes a press fit core comprising two stacks of laminations 41 and 42. Stack 41 is formed from laminations stamped in the form of a hollow rectangle and it will be observed that a portion 43 of the lamination stack is of a narrower width than a portion 44. Shunt portions 45 are integrally stamped with the laminations of stack 41.

The lamination stack 42 comprises the central leg of the shell type core provided by both stacks, and this stack of laminations has a portion 47 of narrower width and a portion 48 of greater width. Portions of the lamination stacks 41 and 42 are of complementary shape, so as to provide suitable joints 49 and 50 between the two core stacks, the dimensions being such that the parts may be assembled with a press fit.

The primary winding 11 and the secondary winding 13 are disposed on the narrower portion 47 of the central leg 42, and are embraced by the narrower portion 43 of the lamination stack 41, whereas the lead secondary winding 12 is disposed on the portion 48 of the central leg which is of greater width, and is embraced by the portion 44 of the lamination stack 41. The dimensions are such that an air gap 46 is provided between the shunt portions 45 and the central leg 42 to provide for the proper reluctance of the leakage path between the lag secondary and the primary.

The lead secondary 12 and the primary 11 are spaced from each other by a sufficient distance to provide leakage paths 52, similar to the leakage paths 34 of Fig. 1.

The operation of the ballast shown in Fig. 3 is substantially the same as that shown in Figs. 1 and 2.

In Fig. 5 is shown the diagram of a modified circuit in which the windings of the ballast are connected as a double wound transformer, as contrasted with the autotransformer of Fig. 4.

The reference numerals of the corresponding parts are the same as the reference numerals used in Fig. 4, with the exception that they are primed. Thus, lead secondary circuit 24' includes secondary winding 12', condenser 14', conductor 18', lamp 16', and portions of connection 21'; whereas, the lag secondary circuit 25' includes secondary winding 13', conductor 19', lamp 17' and portions of connection 21'.

If desired, one of the secondary windings may be connected in autotransformer relationship with the primary, and the other of the secondary windings may be in the usual transformer relationship.

Both of the circuits shown in Figs. 4 and 5 comprise an instant starting lighting system, that is, one which operates without starters.

However, starting circuits 26 and 27, shunted around the lamps 16 and 17, may be provided if desired, as shown by the dotted lines in Fig. 6.

My invention has been described primarily with reference to lighting systems embodying fluorescent lamps; however, it is obvious that it is applicable to lighting systems embodying other types of gaseous conduction tubes, such as neon tubes, or even to other illuminating devices, such as arc lamps which exhibit negative resistance characteristics.

Although only preferred embodiments of my invention have been shown and described herein, it is understood that numerous modifications and changes may be made therein without departing from the spirit of my invention as defined by the appended claims.

I claim:

1. A ballast for a fluorescent lamp system embodying two lamp circuits, said ballast comprising a core having a winding leg and a yoke, a primary winding centrally disposed on said winding leg, a lagging secondary winding disposed on said winding leg at one side of said primary winding, and a leading secondary winding disposed at the other end of said winding leg, said windings being spaced from each other so as to provide for leakage reactance, that portion of said winding leg on which said leading secondary winding is disposed being of greater cross section than the remainder of said winding leg and that portion of said yoke which is adjacent said leading secondary winding being of greater cross section than the remainder of said yoke in order to compensate for the higher voltage in said leading secondary winding.

2. In a gaseous discharge lamp system having a primary circuit, a leading secondary circuit and a lagging secondary circuit, said primary circuit including a primary winding, said leading secondary circuit including a secondary winding, a condenser and a gaseous discharge lamp, and said lagging secondary circuit including a separate secondary winding and a second gaseous discharge lamp of like characteristics, a core structure for said windings designed to operate at or near saturation and comprising two E-shaped stacks of laminations arranged in abutting relationship to provide a shell type core, one of said stacks of laminations linking said lagging secondary winding and said primary winding, and the other of said stacks of laminations linking said leading secondary winding, said latter stack of laminations having a greater cross sectional area in all portions thereof than the cross sectional area in the corresponding portions of said first mentioned stack of laminations, said primary winding being disposed between said secondary windings in end to end relationship on the central leg of said core, and being spaced therefrom to provide flux leakage paths, and a shunt of magnetic material disposed in that flux leakage path which is between said primary and said lagging secondary windings.

3. In a fluorescent lamp system, a ballast for supplying electrically displaced operating cur-

rents to two separately operable fluorescent lamps, said ballast including a core formed from two stacks of E-shaped laminations arranged in abutting relationship to form a shell type core, the cross sectional areas of the legs of one of said stacks being greater than that of the corresponding legs of the other, a lagging secondary winding and a primary winding disposed on the central leg of that stack which is of smaller cross section, and a leading secondary winding disposed on the central leg of the other stack, said windings being spaced from each other in end to end relationship to provide flux leakage paths, and the butt joint between said stacks being opposite the flux leakage path between said primary and said leading secondary windings.

4. A ballast for a fluorescent lamp system embodying two lamp circuits, said ballast comprising a press fit, shell type core having a winding leg portion and a yoke portion, a primary winding centrally disposed on said winding leg portion, a first secondary winding disposed on said winding leg portion at one side of said primary winding, and a second secondary winding disposed at the other end of said winding leg portion, all of said windings being spaced from each other so as to provide for leakage reactance, those parts of said winding leg and yoke portions which are adjacent to said second secondary winding being of greater cross section than the remainder of said core in order to compensate for the increased voltage in said second secondary winding when connected into a leading load circuit.

5. A ballast for a fluorescent lamp system embodying two lamp circuits, a core having a winding leg portion and a yoke portion providing a closed magnetic circuit, a primary winding disposed on said winding leg portion, two secondary windings disposed on said winding leg portion at opposite sides of said primary winding, all of said windings being spaced from each other so as to provide for leakage reactance and being linked by said core, and said secondary windings being proportioned to provide substantially equal starting voltages, those parts of said winding leg portion and said yoke portion which link one of said secondary windings being of greater cross section than the remainder of said core in order to compensate for the increased operating voltage in said last-mentioned secondary winding when connected into a leading load circuit.
